APPARATUS FOR ROLLING SCREWS

William A. De Vellier, New York, N. Y., assignor
to New Process Screw Corporation, Waterville,
Conn., a corporation of Delaware

Application October 2, 1945, Serial No. 619,816

2 Claims. (Cl. 80—8)

1

My invention relates to improvements in the methods and apparatus for rolling screws adapted for rolling double threaded screws and particularly comprises improvements on the methods shown and described in my former Patent No. 2,314,391 for Screw and method of its manufacture, issued March 23, 1943.

While the methods shown and described in said patent are capable of producing commercial screws, in practice a certain variation has developed in the points produced.

An object of my invention comprises the modification of said method to positively produce the right predetermined point, and in practice to successively produce the same shaped points on the double threaded screws shown and described in said patent, in other words, my present invention involves improvements or refinements in the method of rolling screws described in said patent. As stated in said patent, the nature of the point can be changed to that of the various species shown therein and other species by variations in the shape and amount of excess metal on the point forming portion of the blank.

In employing said invention in commercial practice, even with the same amount of excess metal on the pointed portions of the screw blanks, slight variations in the shape of the points in successive screws were produced. All matters of prior or known shop practice were carefully checked, namely the circumference and dimensions of the blanks were measured, and the method of making the dies to the right theoretical dimensions and the method of setting the machine and dies to make the screws roll between the dies to make double threaded screws in accordance with the showing in my copending application for patent, which is now abandoned, Apparatus for rolling double threaded screws, S. N. 598,675, filed June 11, 1945, of which this is a continuation in part, carefully checked and still variations in the points of the screws occurred. It remained for the present inventor to further visualize the fact that in order to make a predetermined point and successively roll screws having substantially identical predetermined points, it was necessary to correctly register the pointed portion forming portions of the screw blanks at the right height between the pointed portion forming portions of the die cavities by supporting a blank at the right height at the initiation of forming threads on said blank and supporting successive blanks as they are rolled on said dies at the same suitable right height at their respective initiations of forming threads on said blanks. It was only after suit-

able means were provided for this purpose and the thorough realization that this method was necessary that the present invention was evolved and screws having substantially identical pointed portions successfully rolled successively. I discovered that once the threads are started right, if the blanks are of a correct circumference and other dimensions, the dies carefully made to correct theoretical measurements and the machine and dies correctly and properly adjusted, screws having substantially identical predetermined points may be rolled if their blanks are initially correctly aimed to be initially correctly grabbed at the right points or height and that the screws will roll at exactly the same height they are started at throughout the remainder of their passage through the dies to successively provide the right threads and the right points. I discovered that it was first necessary to make the blanks and dies right in accordance with prior shop practice and the showing in my said application, S. N. 598,675, and this application, second to provide them with an adequate and proper adjustment as shown in my said application and this application, and finally to aim or start the blanks at the right height as shown and claimed in this application, and that screws having substantially identical points would be successively produced. In accordance with my improved method I positively support the lower ends of said blanks from below, such as by a bottom stop attached to one of the rolling dies or suitably supported between them. I have found that by varying the height of the bottom stop the type of point may be varied of the double threaded screws shown in De Vellier Patent 2,314,391 aforesaid within certain limits. Varying the heights of the bottom stop will vary the type of points produced, the shape or quantity of excess metal on the pointed portions of the blanks remaining constant. Thus while for any substantial change in the nature of the point a variation in the shape and the amount of metal on the pointed portion of the blank is essential, minor compensating or adjusting changes in the point to produce commercial points may be made simply by corresponding changes in the adjustment of the bottom stop.

I support the blanks from below preferably by means of an adjustable bottom stop which positively abuts and supports the lower ends of the screw blanks during this period. As an adjustable bottom stop is employed the point forming portions of the screw blanks may be relatively raised and lowered relative to the point forming

portions of the die face cavities to vary the type of points produced.

Supporting the die blanks from below at this period however has an additional advantage. Quite often in practice screw blanks are not of uniform length and some are often longer than others, thus if the blanks are not supported from below, their lower ends or point forming portions will register at different heights relative to the point portion forming portions of the dies resulting in slight changes in the points produced. However, when the blanks are supported from below as by means of an adjustable bottom stop, the pointed portion forming portions of the blanks will always register at the same place or height relative to the pointed portion forming portions of the dies so as to positively insure the successive production of substantially identical points. If one screw blank happens to be a little longer than the others, the only difference in screws produced is only a slightly longer unthreaded portion on the screw shanks well within standard tolerances.

Further objects of my invention relate to the provision of a novel type of apparatus to carry out my improved method.

These and such other objects of my invention as may hereinafter appear will be best understood from a description of the embodiments thereof shown in the accompanying drawings.

In the drawings, Figs. 1-12 illustrate my invention with the screw blanks being supported from below during the initiation of forming threads thereon.

Figs. 1 and 2 are face views respectively of the stationary and movable dies for rolling double threads on the screw blanks, Fig. 1 additionally illustrating screw blanks at different stages of rolling of the screw threads thereon, the successive positions of the blanks indicating the shape of the threads at substantially the positions shown thereon as the blank is being rolled thereacross, and the preferred type of adjustable bottom stop employed by me for supporting the screw blanks from below during the initiation of forming the threads thereon.

Fig. 3 is a perspective view of my improved stationary die provided with an adjustable bottom stop as shown in Fig. 1.

Fig. 4 is a fragmentary reverse plan view showing the details of the adjustable bottom stop shown in Fig. 3.

Fig. 5 is a side elevation of a completed double threaded screw fabricated in the manner shown in the previous drawings.

Figs. 6-10 are vertical sectional views taken respectively through the two dies along the relative positions of the blank as it progresses to its finished state showing the blank in elevation, Fig. 6 being a vertical sectional view approximately at the initiation of rolling, position *a*, with the blank supported by the bottom stop, Fig. 7 being a vertical sectional view substantially at the second position *b* shown in Fig. 1 reading from left to right, Fig. 8 being a vertical sectional view substantially at the third position *c* shown in Fig. 1, Fig. 9 being a vertical sectional view substantially at the fourth position *d* shown in Fig. 1, and Fig. 10 being a vertical sectional view taken substantially at the completion of the rolling of the screw threads thereon, position *e*.

Fig. 11 is a perspective partially exploded view of the two dies shown in Figs. 1 and 2.

Fig. 12 is a plan view of a suitable die rolling machine with my improved dies mounted thereon having suitable means for adjusting them to provide the oppositely inclined grooves thereof continuously opposite each other to accurately roll double threads.

In the drawings, wherein like characters of reference generally indicate like parts throughout, *78* generally indicates a double threaded screw constructed in accordance with my invention as shown in Fig. 5.

As stated hitherto, my present invention covers improvements in the Method of rolling threaded screws described in my former Patent 2,314,391.

As stated in said patent, it has been customary in the prior art to form pointed portions *75* of conical shape on the screw blanks *98* prior to rolling threads thereon. Great difficulty has been experienced in finding enough metal from such a conically pointed portion of the shank to form threads extending to or beyond the tip *76* of said conically pointed portion *75*, where it is desired to roll double threads as they require considerable metal.

My invention is adapted for use in rolling double threaded screws to successively produce uniform predetermined points thereon. My improved screw has the usual head *72*, the shank *74* and the tapered pointed portion *75* of the shank terminating in the tip *76* and the continuous double threads *78* extending spirally downwardly through at least a portion of said shank *74* and said tapered pointed portion *75*. Each thread *78* preferably tapers outwardly to a sharp continuous spiral cutting preferably razor-like edge *79* of substantially even height throughout the shank *74* and of progressively decreasing height in said tapered portion *75* of the shank. Employing my invention, the lower ends of said threads may form sharp incising means *82* projecting substantially axially downwardly of the pointed portion *75* of said shank.

My invention also involves a novel method of rolling double threaded screws, which comprises after pressure shaping or otherwise forming a length of stock into a blank *98* having a head *72* on one end thereof and an irregular shaped pointed portion *99* having an excess of metal *100* thereon greater than required for a conically pointed portion *128*, as shown in Figs. 1 and 6 on the opposite end thereof, rolling continuous double threads *78* on the other end of the shank *74* adjacent to and on said pointed portion *99* and displacing said excess metal *100* on said pointed portion *99* to form it into the pointed portion *75* of the finished screw and to form continued threads *94* on said pointed portion *75*, each terminating in sharp incising means *82* projecting substantially axially downwardly of said pointed portion *75*. The irregularly shaped pointed portion *99* having an excess of metal *100* thereon greater than required for a conical pointed portion *128* may be formed in any suitable manner, if desired in a separate pointing step, as shown in my Patent No. 2,314,390. I have found, however, that while the formation of a true conically pointed portion *128* has been difficult in the header, my improved pointed portion *99* is of such irregular shape that it may be readily formed in the header, preferably in the initial blow for roughening the head as shown in my Patent No. 2,314,391, or the irregular shaped pointed portion *99* may be made in any suitable fashion.

The threads 78 may be rolled on the screw blanks 98 in any suitable manner, such as in the manner shown in Patent No. 2,314,390 aforesaid, by true radial extrusion. Commercial results, however, may be obtained by rolling them in the type of dies shown in the accompanying drawings, constructed to roll double threads by providing groove means 104 in said dies having a suitable included angle and a pitch angle of from substantially 12 degrees to substantially 22 degrees. I have found that suitable pitch angles for rolling double threaded screws vary from substantially 12 degrees to substantially 22 degrees, namely from substantially 12 degrees for a No. 2 screw to substantially 22 degrees for a No. 18 screw. I have found in practice that if angles below these amounts for the respective size screws be employed in the dies that it is impossible to roll double threads thereon, single threads only being produced. I have also found that if the angle is increased substantially above these amounts for the respective size screws that more than two threads will be rolled thereon. With this type of rolling dies the excess metal 100 is forced or extruded during rolling axially downwardly as well as radially outwardly over the sides of the pointed portion 99 of the shank and even beyond the tip 76 of said simultaneously formed pointed portion 75, if desired, to form the threads 94 of decreasing height terminating in the sharp incising means 82. It is thus obvious that the amount of excess metal 100 provided may be varied, as well as the method and amount of rolling varied to produce these different results. When the desired type of screw has been decided upon, the amount of excess metal 100 provided at the pointed portion 99 of the blank 98 and the nature and the amount of rolling may be predetermined so as to continuously reproduce the same type of screw, the amount of excess metal 100 depending, therefore, upon the desired shape of the incising means 82 desired in the finished screw, the incising means 82 of the desired predetermined shape being produced by variations in the amount of excess metal 100 and the type of and the amount of rolling employed. As stated, if desired, the ends 82 of the threads may terminate slightly above the tip 76 of the pointed portion 75 of the screw shank. While I preferably roll said threads 94 down to an incising point or blade, a novel desirable type of screw may be produced if the threads are not rolled down to a single point or a single blade, but left terminating in spaced incising means 82, on each side of the pointed portion 75 of the screw, in which the screw may initially bite into the wood or other material at two points or portions, tending initially to more evenly align it and provide a self-centering screw as shown in my Patent No. 2,314,391.

I have shown in Figs. 1-4, and 6 to 10 suitable types of dies for rolling the double threads 78 extending at least to the extreme tip 76 of the pointed portion 75 of the shank 74 in accordance with my invention. These dies comprise the usual stationary die 130 and the die 132 movable relatively thereto in a standard type of screw rolling machine, a suitable type being shown in Arenz Patent 1,912,879 and another type in Fig. 11. Each die 130 and 132 has a face 134 comprising a continuous cavity 136 having a flat shank forming portion 146 and a pointed portion forming portion 140 tapering outwardly to the surface of said die beyond said cavity 136. Each face 134 is provided with continuous thread

forming groove means 104, each preferably terminating in a sharp intaglio ridge 106 formed by the sides thereof meeting in a sharp peak, extending obliquely thereof at spaced distances throughout the height of said face throughout the shank forming portion 146 and said pointed portion forming portion 140. The groove means 104 are of substantially even depth along the axis of a screw blank interposed transversely between said dies in use in said shank forming portion 146 and of progressively decreasing depth in said pointed portion forming portion 140 as may be seen in Figs. 6-10. In the embodiments shown, each groove means 104 is also of progressively decreasing depth and width along the length thereof and the successive groove means are of progressively decreasing depth and width throughout the length of the cavity forming cooperating lands 148 between said groove means, of inversely increasing relative width throughout the height of said face through said shank and screw pointed portion forming portions. Thus each respective groove means 104 is of substantially equal depth in said shank forming portion and of progressively decreasing depth in said pointed portion forming portion along the axis of a screw blank interposed transversely between said dies when mounted on a rolling machine in use. In use, the dies 130 and 132 are so mounted that their entire faces 134 remain at a spaced distance from and inclined relative to each other with their respective groove means 104 oppositely inclined, to roll preferably by both axial and radial extrusion double screw threads on the screw blank 98 rolled between them with similar portions of similar grooves 104 in each die continuously opposite similar portions of respective oppositely inclined grooves 104 in the opposite die along the respective successive lines of contact of said dies with said screw blank.

In order to provide the double threads 78, the groove means 104 have a pitch angle varying from substantially 12 degrees to substantially 22 degrees, in the manner hitherto explained. I concave the face 134 of each die with a screw blank cavity and suitably form the thread forming grooves 104 in said cavity, preferably by a suitable hob or milling cutter. It will be noted that the lands 148 between the grooves preferably progressively widen and the grooves 104 themselves preferably progressively narrow lengthwise of the dies. The various positions *a*, *b*, *c*, *d* and *e* that a screw blank assumes in being rolled are shown in Fig. 1 and Figs. 6-10 to illustrate different stages in the act of rolling the threads, the threads being initially roughened out at *a*, the threads 78 themselves progressively narrowed from *b* to *e* and the lanes 152 between the threads 78 progressively widened from *b* to *e*. It is obvious however that the shape, depth and width of the groove means may be suitably varied to produce different types of screws.

A close inspection of Fig. 1 reveals how the excess metal 100 is displaced axially to form the threads 94 from the pointed portion 99 merging into the incising point 82 and to shave down the pointed portion 99 of the screw blank 98 into the pointed portion 75 of the screw. A close inspection of Fig. 1 and Figs. 6-10 illustrates how the length of the screw increases at the different stages as the threads are formed thereon.

As stated hitherto, said dies must be mounted so that their entire faces remain at a spaced distance from each other with their groove means 104 oppositely inclined as shown in Fig. 12 to roll

preferably by axial and radial extrusion, as suggested in Fig. 1, double screw threads on a screw blank rolled between them with similar portions of similar grooves 104 on each die 130 and 132 continuously opposite similar portions of respective oppositely inclined grooves 104 in the opposite die along the respective successive lines of contact of said dies with said screw blanks to produce the double screw threads. It is thus obvious that each die must be adjustable not only vertically within its holder but also so each end thereof may be adjusted vertically or tiltably relative to the other end. In addition, it is preferable if one of the dies preferably the stationary die 132 be tiltably horizontally away from the vertical plane of the other so that there will be greater space between the dies at the start of the rolling. In other words, so that the stationary die may be pivoted horizontally relative to its outer end to give it proper bite and pressure on the blank to start the blank rolling between the dies and at the same time starting to roll the threads. It is obvious that each of these adjustments may be made preferably by the trial and error method on individual screw blanks until the proper adjustment is made when the rolling machine may be run continuously to produce the screws.

I have shown in Fig. 12 a rolling machine 153 equipped with both of these adjustments, namely the vertical adjustment to align the grooves of the dies exactly opposite each other throughout the rolling cycle so that the dies may assume the vertical positions shown in Figs. 6-10 with the grooves continuously opposite each other for rolling double threaded screws and so that there may be room at the feeding end of the dies for insertion of the screw blanks 98 therebetween with the stationary die 130 inclined relative to the movable die 132 to compress the screw blank and hold it in position during rolling and provide the greater spacing 154 shown in Fig. 6 at the point *a*, successively decreasing through Figs. 7, 8 and 9 as shown at 155, 156 and 158 respectively for the positions *b*, *c* and *d* to the narrow spacing 160 shown at the position *e* in Fig. 10.

As shown in Fig. 12 the movable die 132 is suitably mounted in the movable die block 162. The face of the movable die block 162 is provided with a vertical groove 164 for receiving the movable die 132 having an inwardly tapered inner end wall 166 adjacent the cooperatively tapered inner end wall 165 of the movable die 132. The movable die block 162 is vertically channeled to receive the movable die clamp 168, the channel 170 being wider than the clamp 168 to permit the inward and outward adjustment thereof. The inner wall of the clamp 168 adjacent its face is provided with the inwardly tapered end wall 172 abutting the inwardly tapered outer end wall 174 of the movable die 132. The movable die block 162 forms a ram 162 which may be moved inwards and outwards by the connecting rod 176 mounted on the crank pin 178 eccentric of the drive shaft 180 of the rolling machine to reciprocate the movable die block 162 inwardly and outwardly for rolling the screws. The outer end 182 of the movable die block beyond the clamp 168 is provided with an inwardly projecting horizontal threaded hole 184 to receive the adjusting bolt 186 projecting inwardly of the hole 184 from the outer wall of the die block, the inner end of which is adapted to abut the die clamp 168 to clamp it against the outer end of the stationary die 132 to hold the die 132 in adjusted position clamped against the wall 166 of the die block 162 as shown in Fig. 75

12. In order that the grooves 104 of the movable die 132 may be vertically and/or slightly angularly adjusted to be exactly opposite the grooves 104 in the stationary die 130 the movable die 132 is usually of less height than its groove 164, providing suitable space below the movable die 132 for this purpose. Thus when it is desired to adjust the entire die 132 the bolt 186 may be unloosened and the entire die 132 raised and lowered within the groove 164 and when it is desired to adjust the inner end 198 relative to the outer end 192 or vice versa, the bolt 186 may be unloosened and the respective end raised or lowered relative to the other prior to again tightening the bolt 186. In the preferred embodiment shown therefore the entire adjustment of the die is effected by the end clamp for the die provided by the die clamp 168 and its adjusting bolt 186.

The stationary die 130 is similarly adjustable in the stationary die block 194. For this purpose the stationary die block 194 is separated transversely as at 196 near the outer end thereof to provide the movable portion 198 adjustable relative to the stationary portion 199 of the stationary die block 194. The stationary die block is also provided with the vertical groove 208 for holding the stationary die 130 which has an inwardly tapered end wall 202 at its inner end, in the solid portion of the die block and an inwardly tapered end wall 206 at its outer end in the movable portion 198 of the die block. Both the movable and stationary portions 198 and 199 of the stationary die block 194 are provided with the horizontal threaded holes 208 and 209 respectively forming a continuous hole for the insertion of the adjusting bolt 210 therein. The inner end of the bolt 210 is suitably anchored as at 212 in the stationary portion 199 of the stationary die block 194 and it is apparent that the screwing and unscrewing of the bolt will move the movable portion 198 relative to its stationary portion 199 to permit easy vertical adjustment of the stationary die 130 in the die block 194 either the whole die itself or each end thereof as explained for the movable die by loosening the adjusting bolt 210 and moving the desired portions of the die and again clamping the adjusting bolt 210 when the die is in its desired position. It is apparent that with this adjustment for the movable and stationary dies that the respective groove means 104 may be suitably aligned and that by providing the end clamps alone to solely clamp the die any supporting shims thought necessary by the prior art are eliminated.

As stated, in the embodiments shown, I also preferably provide means to tilt the stationary die from a horizontal plane on its outer end 192 as a pivot although either or both of said dies may be so tilted if desired. The stationary die block 194 is mounted on the die bed 214. The die bed 214 is provided with the threaded bolt receiving holes 216 and the die block 194 is provided with cooperating transversely elongated slots 218. Bolts 220 are provided for clamping the stationary die block 194 to its bed 214 transversely adjustable in said slots 218. The external portion of the die bed 214 is provided with the transverse bolt holes 222 adapted to receive the transversely movable bolts 224 having inner ends 226 adapted to abut the external face 228 of the stationary die block 194. Thus when it is desired to adjust the angle of tilt of the stationary die 130, the adjusting bolts 220 are unloosened and the bolts 224 are adjusted transversely relative to each other to tilt the entire die block 194 to

provide sufficient space for insertion of the desired size screw blanks to be rolled at the inner end of the stationary die. When the desired tilt has been attained the bolts 220 are again tightened to clamp the stationary die block 194 to its bed 214.

It is apparent however that any other suitable type of means for adjusting the oppositely inclined grooves 104 in the movable and stationary dies 130 and 132 respectively opposite each other such as by longitudinally sliding the dies 130 and 132 relatively to each other or otherwise may be employed and it is obvious that any suitable type of means for raising or adjustably tilting the face of one die relative to that of the other may also be alternatively employed. The stationary die 130 is also preferably of less height than its co-operating groove 200 so as to provide the space below it for adjusting the stationary die 130 relative to the movable die 132.

As shown, the screws 70 are provided with the threads 76 throughout a greater portion of their length, usually about two-thirds of their over-all length including the heads 72 for a flat headed screw.

I have described hitherto the rolling method and apparatus common to De Vellier Patent 2,314,391. As stated hitherto, my present invention relates to refinements of said method and apparatus to positively produce the right point in use and to successively in use produce identical right points.

In employing said invention in commercial practice, even with the same amount of excess metal on the pointed portions of the screw blanks, slight variations in the shape of the points in successive screws were produced. All matters of prior known shop practice were carefully checked, namely the circumference and dimensions of the blanks were measured, and the method of making the dies to the right theoretical dimensions and the method of setting the machine and dies to make the screws roll between the dies to make double threaded screws in accordance with the showing in my copending application for patent, Apparatus for rolling double threaded screws, S. N. 598,675, filed June 11, 1945, carefully checked and still variations in the points of the screws occurred. It remained for the present inventor to further visualize the fact that in order to make a predetermined point and successively roll screws having substantially identical predetermined points, it was necessary to correctly register the pointed portion forming portions of the screw blanks at the right height between the pointed portion forming portions of the die cavities by supporting a blank at the right height at the initiation of forming threads on said blank and supporting successive blanks as they are rolled on said dies at the same suitable right height at their respective initiations of forming threads on said blanks. It was only after suitable means were provided for this purpose and the thorough realization that this method was necessary that the present invention was evolved and screws having substantially identical pointed portions successfully rolled successively. I discovered that once the threads are started right, if the blanks are of a correct circumference and other dimensions, the dies carefully made to correct theoretical measurements and the machine and dies correctly and properly adjusted, screws having substantially identical predetermined points may be rolled if their blanks are initially correctly aimed to be initially correctly grabbed

at the right points or height and that the screws will roll at exactly the same height they are started at throughout the remainder of their passage through the dies to successively provide the right threads and the right points. I discovered that it was first necessary to make the blanks and dies right in accordance with prior shop practice as shown herein, second to provide them with an adequate and proper adjustment as shown herein, and finally to aim or start the blanks at the right height as shown and claimed in this application, and that screws having substantially identical points would be successively produced.

The blanks hitherto described are passed between the relatively movable dies 130 and 132 with the dies being relatively inclined forwardly from their front to rear ends to produce the spacings shown in Figs. 6-10. To insure that the 15 pointed portion forming portions 99 of each blank are supported, from below, at the right height between the pointed portion forming portions 140 of said cavities 134 on both dies at the initiation of forming threads on said blanks, 20 namely while passing through the position as shown in Figs. 1 and 6, to properly register said blanks for the remainder of their passage between said dies when they are supported by said dies to successively form continuous double or 25 other threads on their shanks adjacent said pointed portions and to successively axially displace and mold said excess metal on said pointed portions to form continuous threads on said pointed portions, terminating in substantially identical sharp incising means of the desired predetermined shape projecting substantially axially downwardly of said pointed portions, on diametrical portions thereof where double threads are rolled to successively produce screws having 30 substantially identical predetermined pointed portions, for this purpose, I provide positive means to support said portions of said blanks opposite said portions of said dies during this 35 period from below as shown in Figs. 1-12. The upper ends of the dies are provided with the filler plates 130f and 132f secured thereto by the 40 screws 131.

I support the blanks from below during this 45 period of initiation of forming of the threads as 50 shown in Figs. 1-12, and, as shown in said figures, for this purpose I employ a bottom stop 230 for abutting and supporting the lower ends of the blanks 98 between the dies 130 and 132 during 55 the initiation of forming threads thereon. In order that quick variations or adjustments may be made in the relative positions of the pointed portions 99 and 140, said bottom stop is preferably vertically adjustable. While said bottom stop 60 may be mounted between the dies 130 and 132 in any suitable manner, in my preferred embodiment I have shown it mounted at the front end of one of said dies, as shown, of the stationary die 130.

65 In the preferred embodiment shown, the front forward corner of the stationary die 130 is cut off to provide the oblique portion 232. A supplemental cavity 234 is also cut obliquely along the top of said portion. The central portion of the 70 oblique portion 232 is provided with a truncated triangular channel 236 extending from the bottom thereof upwardly towards said cavity 234. A cooperating adjustable plug 238 of similar truncated triangular shape but of shorter height is vertically movable up and down within

said channel 236. Said triangular plug 238 is provided with a vertical threaded hole 240 therein. A top plate 250 of a height slightly greater than said cavity 234 fits in said cavity and is secured to the portion of the stationary die below it by means of the screws 252. Said plate 250 is provided with a central hole 254 to receive the adjusting screw 256 therein, the threaded shank 258 of which projects downwardly through the threaded hole 240 in the triangular plug 238. It is obvious that by turning the adjusting screw 256 the vertical height of the plug 238 in the vertical channel 236 may be adjustably varied. The rear edge of the plate 250 from the rear edge of the oblique wall 232 rearwards, inclines downwardly as at 260 to the filler plate 130 for a purpose to be described. The adjustable bottom stop 230 is obliquely bent to have the portion 262 overlie the oblique wall portion 232 and the portion 264 overlie the forward edge of the die and the front part of the die cavity 134 over the pointed portion forming portion 140. The portion 262 of the bottom stop is provided with a central hole 266 to receive the screw 268 projecting within a horizontally threaded hole 270 in the vertically adjustable plug 238. To prevent the bottom stop 230 from pivoting relative to the plug 238, it is preferably supplementally pinned thereto by the pins 272.

To adjust the relative height of the upper edge 274 of the rearwardly projecting end 276 of the bottom stop 230 vertically relative to the pointed forming portion 140, it is obvious that it is merely necessary to turn the adjusting screw 256 registering in the hole 240 in the plug 238 to relatively raise and lower said edge 274 through the medium of raising and lowering the plug 238 mounting said bottom stop 230. As the heads 72 of the blanks 98 are fed in between the dies it is apparent that they are first supported by the upper surface of the top plate 250 as their lower ends 99 abut the upper edge 274 of the bottom stop 230 but that as the inclined plane 260 lowers away from the heads 72 the lower ends 99 are supported solely by the upper edge 274 of the bottom stop 230 as the pointed portion forming portions 99 of the screw blanks 98 approach and contact the pointed portion forming portions 140 of the dies. It is apparent however that any other suitable type of a vertically adjustable bottom stop, may be employed in place of the bottom stop shown.

As stated, I may vary the shape, width, depth, included and pitch angles of the groove means in accordance with the type or size of screw desired to be rolled.

It is apparent, however, that by using my improved apparatus I am enabled to provide a predetermined point and successively reproduce the same point, particularly on double threaded screws of the type shown in said De Vellier Patent 2,314,391, with the other advantages described above.

It is understood that my invention is not limited to the specific embodiments shown and that various deviations thereof may be made without departing from the spirit and scope of the appended claims.

What I claim is:

1. Apparatus for successively rolling substantially identically pointed double threaded screws, comprising a pair of relatively movable rectilinear screw thread rolling dies capable of only rolling double threads, each having a face comprising a continuous cavity extending longitudinally there-

of, having a cooperating inwardly tapered portion at the upper edge thereof, a substantially flat central shank forming portion and a lower screw point forming portion tapering outwardly to the surface of said face beyond said cavity, having a plurality of similar continuous thread forming grooves extending obliquely thereof at a pitch angle of from substantially 12° to substantially 22° and extending throughout the height of said face through said shank and screw point forming portions, of substantially equal depth in said shank forming portions and of progressively decreasing depth in said screw point forming portions along the axis of a screw blank interposed transversely between said dies, of progressively decreasing depth and width at least along the major portion of the length thereof and with successive grooves of progressively decreasing relative depth and width throughout at least the major portion of the length of said cavity forming lands between the grooves that progressively widen throughout at least the major portion thereof, means for mounting said dies so that their entire faces remain at a spaced distance from each other and inclined relatively forwardly from their front to rear ends with their groove means oppositely inclined to roll double screw threads on screw blanks having shanks and screw point forming portions having an excess of metal greater than required for conically pointed portions, rolled between them with the lower ends thereof initially spaced from the lower ends of the cavities and with similar portions of similar groove means in each die continuously opposite similar portions of respective oppositely inclined groove means in the opposite die along the respective successive lines of contact of said dies with said screw blanks and a vertically adjustable bottom stop of limited length at the extreme starting end of one die only for initially abutting and supporting the lower ends of said blanks between said dies so that the screw point forming portions of successive blanks are at the same suitable height between the screw point forming portions of said die cavities at the initiation of forming threads on said blanks, to provide the same amount of material on said blanks moldable and axially displaceable to successively produce screws having substantially identical predetermined screw points.

2. Apparatus for successively rolling substantially identically pointed double threaded screws, comprising a pair of relatively movable rectilinear screw thread rolling dies capable of only rolling double threads, each having a face comprising a continuous cavity extending longitudinally thereof of having a substantially flat central shank forming portion and a lower screw point forming portion tapering outwardly to the surface of said face beyond said cavity, having a plurality of similar continuous thread forming grooves extending obliquely thereof at a pitch angle of from substantially 12° to substantially 22° and extending throughout the height of said face through said shank and screw point forming portions, of substantially equal depth in said shank forming portions and of progressively decreasing depth in said screw point forming portions along the axis of a screw blank interposed transversely between said dies, of progressively decreasing depth and width at least along the major portion of the length thereof and with successive grooves of progressively decreasing relative depth and width throughout at least the major portion of the

length of said cavity forming lands between the grooves that progressively widen throughout at least the major portion thereof, means for mounting said dies so that their entire faces remain at a spaced distance from each other and inclined relatively forwardly from their front to rear ends with their groove means oppositely inclined to roll double screw threads on screw blanks having shanks and screw point forming portions having an excess of metal greater than required for conically pointed portions, rolled between them with the lower ends thereof initially spaced from the lower ends of the cavities and with similar portions of similar groove means in each die continuously opposite similar portions of respective oppositely inclined groove means in the opposite die along the respective successive lines of contact of said dies with said screw blanks and a vertically adjustable bottom stop of limited length at the extreme starting end of one die 20 only for initially abutting and supporting the lower ends of said blanks between said dies so

that the screw point forming portions of successive blanks are at the same suitable height between the screw point forming portions of said die cavities at the initiation of forming threads on said blanks, to provide the same amount of material on said blanks moldable and axially displaceable to successively produce screws having substantially identical predetermined screw points.
